UNITED STATES PATENT OFFICE

2,556,654

EAR ORNAMENT

John Kulak, Edmonton, Alberta, Canada

Application July 9, 1946, Serial No. 682,221

3 Claims. (Cl. 63—14)

1

My invention relates to ornaments and more particularly to ear ornaments.

The object of my invention is to provide an ear ornament, which is held in place by taking advantage of the elevations and depressions of an ear.

Another object of my invention is to provide an ear ornament fitting onto the natural elevations and depressions of an ear and held in place thereon by means of spring pressure.

Other objects of my invention may appear in the following specification describing my invention with reference to the accompanying drawing illustrating a preferred embodiment of my invention.

It is however to be understood that my invention is not to be limited or restricted to the exact construction and combination of parts described in the specification and shown in the drawing, but that such changes and modifications can be made, which fall within the scope of the claims appended hereto.

In the drawing—

Figure 1 is a side elevation of the frame or skeleton of the ear ornament according to my invention, an ornament being indicated in broken lines.

Figure 2 is a sectional view taken on line 2—2 in Figure 3.

Figure 3 is a top plan view of Figure 1, and

Figure 4 is a sectional view taken on line 4—4 in Figure 1.

Figure 5 is a side elevational view showing the ear ornament of the invention in place in the oracle of the ear.

The drawing is executed in an enlarged scale for the sake of clarity.

Referring now in detail to the drawing the ear ornament forming the subject matter of my invention has a tubular body 10.

A sliding member 11 is substantially cylindrical and is adapted to slide into the tubular body 10. On its inner end the sliding member 11 has a circumferential flange 12, which fits snugly in the tubular body 10. Adjacent the rear end of the tubular body a circumferential groove 13 is pressed into the body forming a shoulder 14 on the inside of the body, which permits the sliding member 11 to pass, but engages the flange 12 on said member and prevents it from sliding entirely out of the body.

A helical spring 15 is arranged in the tubular body 10 and abuts the inner end of the sliding member 11 with one of its ends. The other end of the spring 15 abuts the ridge of the curved

web 16 of a stop element 17. This element is substantially U-shaped and each of the flanges 18 thereof is provided with a cutout in its front edge, so that two wing-shaped forwardly extending lugs 19 are formed.

In the front end of the tubular body 10 a diametrically extending groove 30 is provided to receive the ridge of the web 16 of the stop element 17.

10 A pin 20 extends through the lips 31 of the groove 30 and the stop element 17 to support said element on the body, so that the element can execute a slight pivotal movement relative to the body.

15 The spring 15 between the stop element 17 and the sliding member 11 is under permanent compression and, in consequence, urges the sliding member rearwardly in the tubular body 10.

The rear or outer end of the sliding member 11 is narrowed down, as at 21 to form a flat neck. A stop plate 22 is rigidly fastened onto the front end of the flat neck 21, for instance by soldering, and has a forwardly curved outer end 23. A base plate 24 is firmly connected with the flat portion of the stop plate 22 and extends at right angles across the same.

Ornamental bodies of any desired kind may be attached to the stop element 17, the body 10 and the rear stop consisting of the stop plate 22 and the base plate 24. These ornamental designs do not form an essential part of my invention and are therefore only indicated at 25 in the Figure 1 and are not described in detail.

The ear ornament is fastened to an ear (not shown) by pressing the two stops together and inserting them between two natural elevations of the ear. The spring 15 urges the stops firmly against these elevations holding the ornament in place.

40 Having described my invention I claim as new and desire to secure by Letters Patent:

1. An ear ornament including a tubular body, a stop element on said body, said stop element being designed to fit the contour of a first part of the ear, a sliding member arranged in said body, a stop plate on said sliding member outside of the body and a spring arranged in the body between the stop element and the sliding member, said stop plate being shaped to fit the contour of a second part of the ear, a circumferential flange on the inner end of the sliding member and an inwardly extending shoulder in the body to limit the outward sliding movement of the element, the stop element being substantially U-shaped, the curved web of the element being located in

a diametrically extending groove in the end of the body opposite to the sliding member, and a pin extending through the lips of said groove and the web of the element and supporting the element pivotally thereon.

2. An ear ornament including a tubular body, a stop element on said body, said stop element being designed to fit the contour of a first part of the ear, a sliding member arranged in said body, a stop plate on said sliding member outside of the body and a spring arranged in the body between the stop element and the sliding member, said stop plate being shaped to fit the contour of a second part of the ear, a circumferential flange on the inner end of the sliding member and an inwardly extending shoulder in the body to limit the outward sliding movement of the element, the stop element being substantially U-shaped, the curved web of the element being located in a diametrically extending groove in the end of the body opposite to the sliding member, and a pin extending through the lips of said groove and the web of the element and supporting the element pivotally thereon, and a rear stop securely attached to the sliding member.

3. An ear ornament including a tubular body, a stop element on said body, said stop element being designed to fit the contour of a first part of the ear, a sliding member arranged in said body, a stop plate on said sliding member outside of the body and a spring arranged in the body between the stop element and the sliding member, said

stop plate being shaped to fit the contour of a second part of the ear, a circumferential flange on the inner end of the sliding member and an inwardly extending shoulder in the body to limit the outward sliding movement of the element, the stop element being substantially U-shaped, the curved web of the element being located in a diametrically extending groove in the end of the body opposite to the sliding member, and a pin extending through the lips of said groove and the web of the element and supporting the element pivotally thereon, and a rear stop securely attached to the sliding member, the rear stop consisting of a stop plate having a curved outer end and a base plate extending across the stop plate, the two plates being rigidly mounted on a neck formed on the outer end of the sliding member.

JOHN KULAK.
